INITIAL MOUNTING

Henry J. Le Blanc, Attleboro Falls, Mass., assignor
to Swank, Inc., a corporation of Delaware

Application November 17, 1950, Serial No. 196,302

4 Claims. (CL 40—140)

1

This invention relates to a mounting of an initial or some other character upon a base for personalized identification or ornamentation.

One of the objects of this invention is to provide a base which may be so formed that any number of initials or characters may be mounted therein by the retailer at the time the sale of the article carrying the identification is made.

Another object of the invention is to provide a construction which will be self-contained and so arranged that when the initial or character is slid into position, it will be automatically locked in the position which it is desired the same to assume, making adjustment unnecessary.

Another object of the invention is to provide a construction which will enable simple manufacture, and thus a more inexpensive construction to produce.

Another object of the invention is to provide a construction in which the initial or character will be raised above the base in relief effect.

With these and other objects in view, the invention consists of certain novel features of construction as will be more fully described and particularly pointed out in the appended claims.

Figure 1 is a perspective view of one of the initials or characters which is constructed in accordance with this invention.

Figure 2 is a perspective view, showing the base with a groove therein, for receiving the character in Figure 1, and illustrating in another position the character, as mounted in a slot in the base.

Figure 3 is a sectional view on substantially line 3—3 of Figure 2.

Figure 4 is a sectional view on substantially line 4—4 of Figure 2.

In proceeding with this invention, I utilize a solid base and cause a cutter to enter one edge of the block and move inwardly at a substantially uniform depth to a point short of the opposite edge of the block to provide a first or main slot, and also mill two intersecting slots at right angles to the main slot so produced. A character which is to be mounted on the base of the block is provided with a member which is of a shape to fit the main slot formed in the block from one edge thereof. This member is of a length less than the width of the block and of a length so that it will be accommodated in the first or main slot mentioned. Locating means, such as an abutment for the inner end of the member, is provided, and also a spring to lock into one of the slots for holding the member in place.

With reference to the drawings, 10 designates a block which is shown of rectangular shape with

15 a top wall 11 and opposite edges 12 and 13. A conical or frustro-conical cutter is then inserted into the edge 12, so as to cut through the face 11, and is caused to enter point 14 which is short of the edge 13. The cutter is shaped so as to provide an undercut first or main slot 15 which is here shown as dovetailed. This slot has a bottom wall 16 and overhanging side walls 17 and 18. Any desired number of slots 15 may be formed in 20 the block identical with the slot just described. These slots will run in parallel relations, as shown in Figure 2, across the slots 15.

I provide a second slot 19 which runs at right angles to these slots 15, and is of a depth to extend into the bottom wall 16 of these slots thus intersecting with the slots 15. A piece of spring wire, 20, is located in this slot 19, with arched portions 21 at the location of each of the main slots 15, to extend through the bottom wall 16 25 and into the slot 15. In order to hold this spring wire in place, there is a closure 22 provided with raised end portions 23 to abut the bottom of the slots 19, while there is a cut-away portion to accommodate the wire 20 therein.

25 A third slot 24 is milled across the slots 15 adjacent their inner ends 14, at a point at the ends of the parallel edges of walls 17 and 18 of the slots 15. Slot 24 is provided with a strip 25 which extends into the slot 15 to provide an abutment 30 to be engaged by anything slid into the slot.

A character which is to be mounted on the base is designated 26, and shown in perspective in Figure 1, which in the case illustrated is the letter "I," and which is of a dimension substantially 35 the dimension between the opposite edges 12 and 13 of the block. Member 27, of a shape corresponding to the undercut shape of the groove 15, is secured beneath the character 26, and is of a length substantially the length between the abutment strip 25 and the edge 12 of the block.

Member 27 is dovetailed, as shown in the drawing, to correspond to the dovetail slot 15, and thus has tapering side walls 28 and 29, and a bottom wall 30. This bottom wall 30 is tapered, as shown 45 at 31, in Figure 4, so that when the member 27 is slid into the open end 32 of the slot 15, it will slide over the arched portions 21 of the spring. This member 27 will be slid into the slot 15 while its end 33 engages the abutment which will 50 serve to locate the character 26 in alignment with the opposite edges 12 and 13 of the block.

In order to lock this character and member in this position, a groove 34 is provided across the member 27, at a location to receive the arched 55 spring 21, which snaps into this groove and locks

the assembly in place. Each initial may be individually inserted in slot 15, and thus be locked into place as it is located in its proper position and in its opening.

By this arrangement, it makes it unnecessary to close the opposite end of the slot while the initial serves to cover the unoccupied main slot which is left by the milling cutter as the slot 15 is formed.

I claim:

1. A mounting for a character comprising a base having an undercut slot in one face thereof opening into one edge of the base to provide an entrance end and terminating short of the opposite edge of the base, a character of a dimension greater than the length of said slot having secured thereto a member of a cross sectional shape to fit into said slot to hold the character above the surface of the base, said member being slidable from the slot through the end thereof opening into said edge.

2. A mounting as in claim 1 wherein an abutment is provided to engage the inner end of said member, and limit its insertion into said first slot.

3. A mounting for a character comprising a base having an undercut slot in one face thereof opening into one edge of the base to provide an entrance end and terminating short of the opposite edge of the base and a second slot extending at an angle to the said first slot and intersecting the same at the bottom of the first slot and adjacent the entrance of the first slot, a spring located in said second slot and protruding into the first slot through the bottom wall thereof, a character of a dimension greater than the length of said slot having secured thereto a mem-

ber of a cross sectional shape to fit into said slot to hold the character above the surface of the base, said member being slidable from the slot through the end thereof opening into said edge and provided with a groove receiving said spring to hold it in said slot.

4. A mounting for a character comprising a base having an undercut slot in one face thereof opening into one edge of the base to provide an entrance end and terminating short of the opposite edge of the base and a second slot extending at an angle to the said first slot and intersecting the same at the bottom of the first slot and adjacent the entrance of the first slot, a spring located in said second slot and protruding into the first slot through the bottom wall thereof, a character of a dimension greater than the length of said slot having secured thereto a member of a cross sectional shape to fit into said slot to hold the character above the surface of the base, said member being slidable from the slot through the end thereof opening into said edge and provided with a groove receiving said spring to hold it in said slot, said member tapered depthwise of said first slot with its leading edge of a depth to slide over said spring and depress the spring as it is moved into the slot.
